UNITED STATES PATENT OFFICE.

ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

WIRE TIE AND SEAL MAKING AND APPLYING TOOL.

Application filed December 20, 1920. Serial No. 431,836.

To all whom it may concern:

Be it known that I, ADELMER M. BATES, a citizen of the United States, residing at Chicago, in the county of Cook and State of Illinois, have invented a certain new and useful Improvement in Wire Tie and Seal Making and Applying Tools, of which the following is a specification.

My invention relates to improvements in tools for making seals for packages, doors, receptacles, and the like and for process of making and applying the same, and has for one object to provide a new and improved form of seal which can be made of wire and which is, itself, the seal, being formed of an integral piece of wire without any additional apparatus or mechanism forming a part of the seal. Another object is to provide a combined seal and tie which cannot be untied or unsealed without being destroyed or at least without being so disturbed or distorted that it cannot again be used as a seal or a tie. I have discovered that when a piece of metallic wire is wrapped about an object or passed through an aperture to be sealed and the two ends are twisted together until they break off at a point removed from the body of the tie, it thereby creates a seal which takes the form of the tightly twisted tie ends and I have discovered that when sufficient twisting and tension is applied to cause the ends of the wire to break off beyond the twisted seal portion, that part of the wire which forms the twisted sealing end being stretched and heated clear up to the elastic limit, can never again be untwisted without breaking or without taking on a permanent distortion and thus can never be twisted together again so as to simulate the appearance of the originally twisted or formed seal.

When a wire is used, it is of course, impossible to have any member or object which carries any number or mark and it might seem to be possible to easily reproduce the characteristic seal. This is, however, not the fact because the seal can be made of a particular color, shape or character of wire and arrangements can be made to protect or limit the manufacture or sale of such particular shape, type or color so that any one who desired to tamper with the seal would have as much difficulty getting such wire and getting such material as will make the seal,

as would one who desired to tamper with the ordinary lead seal.

My invention is illustrated more or less diagrammatically in the accompanying drawings wherein:

Figure 1 is a view of a package with the wire tie and seal about to be applied;

Figure 2 is a view showing the tie twisted but before the ends are broken off to make the seal;

Figure 3 is a view showing the complete package tie and seal;

Figure 4 is an end view of the twisting tool;

Like parts are indicated by like characters throughout the drawings.

A is a cylindrical handle, knurled and corrugated as at A' to furnish a satisfactory grip to the operator. At the further end of the handle is a nut A² having a spiral engaging device of some kind not here shown since it forms no part of my invention. Slidably and rotatably within the handle is the spiral A³ engaging the nut A², the arrangement being such that when the spiral is drawn, it is moved by its engagement with the nut to rotate. A⁴ is a twisting head on the end of the spiral; it is provided with a forward wall A⁵ slotted at A⁶ and behind this wall is a pocket A⁷.

B is a package or in this case bag, which is to be tied or sealed. B' is a wire tie having at its two ends the upset ends or heads B². The ends of the tie pass down in through the slot A⁶, the heads being in the pocket A⁷ and resting within the back side of the wall A⁵. The loop of the tie is passed around the neck of the bag. The operator then holds the bag, and pulling on the handle exerts a tension by causing the spiral to pass out from the handle and rotate. This rotation causes the two ends of the tie to be twisted together as shown in Figure 2. At some point during this rotation the tie materially is twisted beyond its elastic limit and twisted off as shown in Figure 3, leaving the tie or seal twisted around the neck of the bag or around the package with the material end of the tie stressed, perhaps even beyond its elastic limit. Both ends of the tie are broken off at a certain point, which experiments show, is always at the tool and not at the handle.

C is a plunger having a head C' adapted

to slide in the slot A⁶. C² is a spring surrounding the plunger tending normally to hold it in the position shown in Figures 1 and 3. When the plunger is forced upward, as for instance by striking it on a rigid structure the head C' moves up through the slot and ejects the broken off ends of the tie.

The use and operation of my invention are as follows:

- 10 10. The operator who is going to apply the tie or combined tie and seal, first takes the seal forming wire, passes the bight thereof around the open mouth of the bag or around a package or through the lock or hasp of a lock as the case may be. He then takes hold of the two ends of the wire by a hook passing through the loops or by a slotted twisting head engaging the two upset ends and he then either by using a helical or spiral 15 twisting tool or by twisting the wire by hand, as the case may be, twists the free ends of the wire together so that the tie exerts a tension on the member about which it is passed and so that the spiral or twisted 20 ends extend out from the body of the tie a suitable distance. This twisting continues until the free ends which are held by the twisting tool are caused to break off leaving a projecting stub made up of the two twisted 25 ends of the wire tie and this projecting stub forms the seal and at the same time, holds the ends of the tie together.

I claim:

- 30 1. In a wire seal making tool a twisting head having a pocket open at one side, one of the side walls of the pocket being slotted and an ejector member located within the pocket and mounted for slideable movement within the slot.
- 35 2. In a wire seal making tool a twisting head having a pocket open at one side, one of the side walls of the pocket being slotted and an ejector member located within the pocket and mounted for slideable movement within the slot said ejector comprising a plunger slideable in one wall of the pocket and having a tongue slideable in the slot.
- 40 3. In a wire seal making tool a twisting head having a pocket open at one side, one of the side walls of the pocket being slotted and an ejector member located within the pocket and mounted for slideable movement within the slot said ejector comprising a plunger slideable in one wall of the pocket and having a tongue slideable in the slot, and yielding means for holding the plunger and tongue normally at the bottom of the slot.
- 45 4. In a wire seal making tool a twisting head having a pocket open at one side, one of the side walls of the pocket being slotted and an ejector member located within the pocket and mounted for slideable movement within the slot and yielding means for normally holding the ejector in the initial position.
- 50 5. A wire seal making tool comprising head and means for rotating the head having a slot adapted to engage the wire tie and means carried by the head for positively ejecting the ends of the tie from the slot.
- 55 6. A wire seal making tool comprising a rotatable head having a slot adapted to engage the wire tie and means carried by the head for positively ejecting the ends of the tie from the slot, said ejecting means comprising a plunger slidably mounted in the head and an ejector tongue carried thereby and slideable in this slot.
- 60 7. In a wire seal making tool a twisting head having a pocket open at one side, one of the side walls of the pocket being slotted and an ejector member located within the pocket and mounted for slideable movement within the slot, the slot terminating at its outer end in a flared enlargement to guide the tie head into the slot.
- 65 8. A wire seal making tool comprising a hollow handle, a rod mounted slidably therein and means interposed between the handle and rod for giving the rod a rotary movement responsive to relative longitudinal displacement of handle and rod and a twisting head on the rod comprising a slotted end wall adapted to engage and hold the upset ends of the seal forming tie, a perforated wall perpendicular to the end wall and a plunger mounted for longitudinal movement in said perforation.
- 70 9. A wire seal making tool comprising a hollow handle, a rod mounted slidably therein and means interposed between the handle and rod for giving the rod a rotary movement responsive to relative longitudinal displacement of the handle and rod and a twisting head on the rod comprising a slotted end wall adapted to engage and hold the upset ends of the seal forming tie, a perforated wall perpendicular to the end wall and a plunger mounted for longitudinal movement in said perforation, the head on plunger having a tongue penetrating into and slideable within the slot.
- 75 10. A wire seal making tool comprising a hollow handle, a rod mounted slidably therein and means interposed between the handle and rod for giving the rod a rotary movement responsive to relative longitudinal displacement of handle and the rod and a twisting head on the rod comprising a slotted end wall adapted to engage and hold the upset ends of the seal forming tie, a perforated wall perpendicular to the end wall and a plunger mounted for longitudinal movement in said perforation, the head on plunger having a tongue penetrating into and slideable within the slot.
- 80 11. A tool for applying wire seals, com-

- prising a wire tie engaging twisting head and means for rotating it, and means independent thereof for ejecting the ends of the tie from the head.
- 5 12. A tool for forming wire ties comprising a head and means for twisting it to form the tie and break off the working ends thereof, and means for ejecting the broken off heads.
13. A tie engaging member comprising a 10 slotted head, and ejecting means comprising a plunger adapted to travel along the slot.

Signed at Chicago, county of Cook, and State of Illinois, this eleventh (11th) day of December, 1920.

ADELMER M. BATES.
